Inventor:

JOSEPH D. MCKEE

United States Patent Office.

JOSEPH D. McKEE, OF PHILADELPHIA, PENNSYLVANIA.

Design No. 3,191, dated September 1, 1868.

DESIGN FOR PATTERN FOR KNITTED FABRIC.

The Schedule referred to in these Letters Patent and making part of the same.

TO ALL WHOM IT MAY CONCERN:

Be it known that I, JOSEPH D. McKEE, of city and county of Philadelphia, and State of Pennsylvania, have invented a new Design for a Knitted Fabric; and I do hereby declare that the accompanying photographic representation fully exhibits my said design.

What I claim as my invention, and desire to secure by Letters Patent, is—

The design for a knitted fabric, substantially as represented and set forth.

To the above, I have signed my name, this nineteenth day of August, 1868.

JOS. D. McKEE.
